UNITED STATES PATENT OFFICE.

CLARENCE DOUGLAS BROWN, OF BAY SIDE, NEW YORK.

LOOSE-LEAF BOOKLET.

Application filed May 14, 1924. Serial No. 713,117.

To all whom it may concern:

Be it known that I, CLARENCE DOUGLAS BROWN, a citizen of the United States, residing at Bay Side, Long Island, in the county 5 of Queens and State of New York, have invented certain new and useful Improvements in Loose-Leaf Booklets, of which the following is a specification.

This invention relates to booklets adapted 10 for general use and especially for widespread commercial circularization, and more particularly to booklets having standardized covers and interchangeable fillers that vary in subject matter adapted for ready 15 assemblage and engagement within said covers.

An object of this invention is to provide 20 a booklet cover which may be made up in large quantities to be kept in stock and used 25 as desired as a carrier of one or more issues or editions of fillers, the cover being so constructed as to render it suitable and convenient to receive the successive editions of 30 fillers from time to time.

Another object of this invention is to provide 35 a filler composed of leaves which in any issue or edition are usually uniformly alike as to size and form, said filler being adapted to be received and held by one of the aforesaid covers, whereby when it is desired to 40 make up a number of booklets for purposes of circularization or the like, the filler having a predetermined printed content is rapidly and cheaply engaged within the covers, 45 the booklet being thus complete.

Another object of this invention is to provide 50 a booklet having engaging means for the filler comprising an eyelet or the like whereby the booklet may be suspended by a hanger threaded through the eyelet.

With the foregoing and other objects in view the invention consists in the arrangement and combination of parts hereinafter described and claimed, and while the invention 55 is not restricted to the exact details of construction disclosed or suggested herein, still for the purpose of illustrating a practical embodiment thereof reference is had to the accompanying drawings, in which like reference characters designate the same parts in the several views, and in which—

Figure 1 is a perspective view of my booklet with the cover partly broken away to show the manner of engagement of the filler and the cover.

Fig. 2 is a perspective view showing an

open cover and one method of inserting a filler into the cover.

Fig. 3 is a view of a leaf showing its engaging means.

Fig. 4 is a view of a leaf having a modified engaging means.

The cover 10 consists preferably of a single sheet or strip of paper or the like bent or folded upon itself along a line 11, the portions of the cover adjacent to such line forming a back along which either or both of the cover pages or sides may be hinged at 12. The cover is made of any suitable material or quality according to the intended purpose but which preferably is fairly flexible and yet thick enough to possess a certain amount of stiffness. The cover can now be said to consist of two main portions, the back 13 which is substantially of flat U-form comprising that part of the cover adjacent to the folding line and between the hinge lines 12 and the sides or cover pages 14 extending from the hinge lines to the free edges of the cover.

In the practice of this invention the cover is provided at the ends of the back and between the folding line 11 and the hinge line 12 with some suitable holding or locking means which has the function of forming within the back a pocket 15 adapted to receive and hold, more or less permanently, the filler leaves of the booklet. Said pocket is preferably so constructed that it has an undercut or end extension 16 leading toward each extreme rear point or corner of the back for a purpose soon to appear. Said holding or locking means may assume various forms, but for the sake of simplicity and cheapness of construction, I have indicated the same in the form of hollow rivets or eyelets 17 and 17' driven directly through the end portions of the pocket and not far to the rear of the hinge line, thus providing between the rivets a pocket with a neck having a constant perimeter. In forming the pocket, the eyelets grip the adjacent side portions of the cover back against each other, no washer or collar about the eyelet being ordinarily necessary or desirable between the contacting portions aforesaid for the sake of simplicity and cheapness in construction. A hanger or string 18 may now be threaded through the eyelet 17 if desired to permit the assembled booklet to be suspended from a nail or the like.

The cover may of course have any suit-

able title, design, or other information which is intended to be permanently used in connection with the circularization or other work for which the booklets are intended to be printed, pressed, or otherwise indicated therein.

The leaf 19 is of suitable size and form adapted to be received within the cover. All the leaves will be of the same construction 10 and may thus be used interchangeably with any standard cover. The printed matter thereon, however, will vary from time to time to suit the user's varying business requirements.

15 As shown in Fig. 3 the leaf 19 has a hinge line 20 formed adjacent to a side edge thereof and parallel to said edge. Notches 21 are cut or otherwise formed at the upper and lower corners of the leaf along the side 20 aforesaid. The notches are preferably of V-form, forming acute angles or points 21', and the adjacent edges of the V's are inclined toward each other thereby forming a dovetail locking tongue which is of a size 25 greater than the neck of the pocket 22. This tongue is adapted to enter the pocket 15 and with said points engaging behind the eyelets 17 and 17' to retain the leaf within the cover. The notches 21 are so formed 30 that they are adapted for easy and rapid reception of the eyelets, and consequently the locking tongue can be inserted into the pocket 15 with ease and rapidity.

To insert a filler, which may comprise one 35 or more leaves, into the cover, the cover is opened somewhat as shown in Fig. 2, and one end portion or point 21' of the tongue is projected directly into its seat 16 by a motion such as that indicated by the arrow 40 *a*. The filler is then flexed or buckled by forcing it in the direction indicated by the arrow *b* against the eyelet 17 whereby the effective length of the tongue is decreased so that the other point thereof can be inserted into its pocket or seat 16 to engage 45 behind the eyelet 17' as indicated by the arrow at *c*. The flexibility of the cover allows for sufficient spreading of the pocket to permit the flexing and inserting action aforesaid through the neck of constant perimeter, and when so inserted the filler will lie in straight or flat position and the cover may 50 then be closed. The normal tendency of the back 13 will be to retain the filler in such flat position and consequently the locking tongues in engagement with said eyelets. The booklet is now completely assembled.

A modification of my leaf is shown at 19' 55 in Fig. 4. The lower notch 23 is formed with an edge substantially at right angles to the back edge of the leaf, thereby eliminating the necessity for flexing the leaf or buckling it to insert the same into the cover. Thus after engaging the upper point 21' of

the tongue 22' behind the eyelet 17, as shown 65 by the arrow *a'*, the leaf is rotated clockwise about this eyelet until the tongue 22' has passed the eyelet 17' and entered the pocket 15, the direction of insertion being then indicated by the arrow *b'*. The lower portion 70 of the tongue thus abuts against the eyelet and prevents a downward movement of the filler and the consequent disengagement of the upper portion of the locking tongue. Hence in both forms shown the filler will be 75 self retained in the cover by virtue of the dovetail point 21' interlocking back of the holding means 17, and so the weight of the 80 filler will not cause the same to slip from the cover even though the structure be hung up by the loop 18.

I claim:

1. In a booklet, the combination of a cover having a substantially flat U-shaped back forming a pocket, said cover being flexible 85 longitudinally thereof, a plurality of fastening means lying adjacent to the ends of the back and securing in direct contact with each other the sides of the U-shaped back to form an effective dovetail pocket having a 90 neck with a constant perimeter, said pocket being opened by flexing apart the sides thereof at a point between said fastening means, and a filler inserted into said pocket when the same is opened as aforesaid and 95 having points interlocking behind said fastening means.

2. In a booklet, the combination of a cover having a U-shaped back forming a pocket, said cover being flexible longitudinally 100 thereof, a plurality of fastening means lying along the back and securing together the sides thereof in direct contact to form an effective dovetail pocket therebetween having a neck with a constant perimeter, said 105 pocket being opened between said fastening means by flexing the pocket, and a filler which is inserted into said pocket when the same is opened as aforesaid, and having a tongue to lock behind said fastening means 110 of larger size than the size of said neck, said cover and filler having sufficient stiffness to lie flat when assembled.

3. In a booklet, the combination with a 115 filler having a locking tongue, of a cover having a thin flexible back and a pocket in said back having a longitudinal opening formed therein of smaller size than the size of the locking tongue, said opening being expandable transversely by flexing the sides of 120 said pocket away from each other between the ends of the pocket and about the edge of said back, so as to render said tongue insertable into said pocket through said opening.

4. In a booklet, the combination with a 125 filler having a locking tongue, of a cover having a thin flexible pocket to receive said tongue, said pocket having for this purpose

an opening between the sides of the pocket, said opening being of smaller size than the size of the locking tongue, said pocket having a substantially straight line back opposite to said opening, said sides being secured together against movement toward or from each other at the ends of said opening, but

said sides being flexible away from each other between the ends of said opening and about said straight line back for the purpose of expanding said opening to receive said tongue. 10

In testimony whereof I affix my signature.
CLARENCE DOUGLAS BROWN.
